ATTORNEY

UNITED STATES PATENT OFFICE

ALBERT MOMM, OF IRVINGTON, NEW JERSEY, ASSIGNOR TO AUGUST GOERTZ & CO. INC.,
A CORPORATION OF NEW JERSEY

SNAP FASTENER

Application filed May 8, 1931. Serial No. 535,826.

This invention relates, generally, to fasteners or catches; and the invention has reference, more particularly, to a novel snap fastener having a pivoted latch bar adapted to be snapped to locked or unlocked position, the said snap fastener being adapted for use on containers, such as hinged boxes or the like.

Heretofore, fasteners provided with pivot-
ed latch bars as generally constructed, were
not of the snap type and had no means for
retaining the latch bar in either locked or
unlocked position, so that the same would
often accidentally move or shift from locked
position to unlocked position or vice versa.

The principal object of the present invention
is to provide a novel and ornamental snap
fastener having a pivoted or swivel latch bar,
together with means adapted to cooperate
with said bar whereby the same is retained
in either locked or unlocked position, the said
bar being adapted to be snapped from one
position to the other.

Another object of the present invention lies
in the provision of a novel snap fastener
which is of extremely simple construction and
is strong and reliable in operation.

Other objects of this invention, not at this
time more particularly enumerated, will be
clearly understood from the following de-
tailed description of the same.

The invention is clearly illustrated in the
accompanying drawing, in which:

Fig. 1 is a perspective view of a box having
a hinged cover, which cover is adapted to be
fastened to the body of the box by the novel
snap fastener of the present invention.

Fig. 2 is an enlarged rear view of the snap
fastener taken along line 2—2 of Fig. 1.

Fig. 3 is an enlarged sectional view taken
along line 3—3 of Fig. 2.

Fig. 4 is a view similar to Fig. 2 but illus-
trates the operation of the swivel latch bar.

Fig. 5 is an enlarged sectional view taken
along line 5—5 of Fig. 4; and

Fig. 6 is a perspective view of the spring
plate.

Similar characters of reference are em-
ployed in all of the hereinabove described
views, to indicate corresponding parts.

Referring now to said drawing, the refer-
ence numeral 1 designates the body section
of a box or other container having a cover
portion 2 which is hingedly connected to the
body portion 1 at the rear of the box. The 55
novel snap fastener of this invention is illus-
trated in Fig. 1 as consisting of two cooperat-
ing halves, a lower half 3 and an upper half
4. The lower half 3 is attached to the front
wall of the body section 1 adjacent the upper 60
edge of this body section, and the upper half
4 of the fastener is attached to the cover 2
for cooperation with the lower half 3.

As especially shown in Figs. 2 to 6, the
lower half 3 of the snap fastener is illustrated 65
as comprising a hollow casing providing a
substantially semi-circular front wall, to-
gether with wing projections 5 formed at the
sides of the front wall, which wing projec-
tions are provided with apertures for receiv- 70
ing attaching screws 6. The top or upper
wall 7 of the lower fastener half 3 is posi-
tioned so as to be substantially flush with the
top of the body portion 1 of the container.
Wall 7 is formed with an opening 8 for re- 75
ceiving the hooked end 10 of a swivel latch
bar 11 which is pivotally mounted upon a
pin 12 carried by the upper half 4 of the snap
fastener. The hooked end 10 is adapted to en-
gage the wall 7 of the lower fastener half 80
to thereby lock the two halves together.

The upper half 4 of the snap fastener is
similar in construction to the lower half 3
and has a substantially semi-circular front 85
wall which is complementary to the front
wall of the lower fastener half. Upper half 4
is provided with an arcuate slot 13 in the up-
per curved wall thereof through which the
handle portion 14 of the swivel latch bar 11
extends for manipulative engagement by the 90
fingers of the user. The bottom wall of the
upper half 4 is provided with an opening 15
through which the hook portion 10 of the
swivel latch bar is adapted to move.

In order to cause the swivel latch bar 11 to 95
snap from locked to unlocked position or vice
versa, a semi-circular spring plate 16 is con-
tained within the interior of the upper half
4 of the snap fastener and this spring plate
is interposed between the vertical wall of the 100

upper half 4 and the latch bar 11. The spring plate 16 has an aperture 17 for receiving the pivotal pin 12 and is formed with a rearwardly directed upper bowed portion 18 for co-operating with the handle portion 14 of the swivel latch bar. The bowed portion 18 is positioned directly above the pivotal pin 12 and the handle 14 moves past this bowed portion 18 in moving from locked to unlocked position. This bowed portion 18 by pressing against handle 14 resists the initial movement of the latch bar in either direction, but as the handle 14 passes the vertical or dead-center position, this arcuate portion acts to assist the movement of the latch bar and causes the same to snap into its final position, which final position is either the locked or unlocked positions of the latch bar. When the latch bar is in either its locked or unlocked position, the arcuate bowed portion 18 serves to retain the latch bar in such position, inasmuch as it requires a definite finger pressure to force the latch bar handle 14 over the arcuate portion 18.

In use, the novel snap fastener of this invention has a definite snapping action when moved to locked or unlocked position or vice versa, which snapping action is obtained by the simple expedient of using the spring plate 16. As it will be apparent the novel snap fastener of the present invention is of extremely simple construction and yet is positive and reliable in operation owing to the use of the spring plate 18 which insures the fastener remaining in locked or unlocked position, as desired, and prevents the latch bar from moving from one position to the other accidentally. It will be apparent that the casings 3 and 4 may be reversed so that casing 3 is attached to the cover portion 2 and casing 4 is attached to the body section 1 of the container, if desired.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

1. A snap fastener for containers having hinge sections or the like comprising, an upper casing portion and a lower casing portion adapted to be secured to the cover and body sections, respectively, of a container, said casing portions having similar front walls and being open at their rear, a pivotal pin secured to said upper casing portion front wall, a swivel latch bar pivotally mounted upon said pin, said swivel latch bar having a hooked end for engaging said lower casing portion in locked relation, said upper casing portion having a slot in the upper surface thereof, and a handle formed on said swivel latch bar

and extending through said slot and exteriorly of said upper casing portion for manual manipulation, and a spring plate mounted on said pivotal pin and interposed between said upper casing portion front wall and said latch bar, said spring plate having a bowed portion projecting into the path of movement of said handle for engaging the handle of said latch bar to thereby retain said handle in either locked or unlocked position and causing said latch bar when manipulated in use to snap from one of these positions to the other.

2. A snap fastener for containers having hinge sections or the like comprising, an upper casing portion and a complementary lower casing portion adapted to be secured to the cover and body sections, respectively, of a container, said casing portions having similar front walls and being open at their rear, a pivotal pin secured to said upper casing portion front wall, a swivel latch bar pivotally mounted upon said pin, said swivel latch bar having a hooked end for engaging said lower casing portion in locked relation, said upper and lower casing portions being apertured to permit movement of said hooked end from said upper casing portion and into said lower portion, said upper casing portion having a slot in the upper surface thereof, and a handle formed on said swivel latch bar and extending through said slot and exteriorly of said upper casing portion for manual manipulation, and a substantially semi-circular spring plate mounted on said pivotal pin and fixedly interposed between said upper casing portion front wall and said latch bar, said spring plate having a rearwardly directed bowed portion for engaging the handle of said latch bar to thereby urge said handle to either locked or unlocked position and causing said latch bar in use to snap from one of these positions to the other.

3. A fastener for containers comprising, two casing portions, said casing portions having complementary front walls, together with top, bottom and side walls, the bottom of one of said casing portions and the top of the other casing portion having openings therein adapted to substantially register with one another when said casing portions are superimposed one upon the other, a swivel latch bar pivotally mounted within one of said casing portions and having a hooked end adapted to be moved outwardly of said one casing portion to extend through said casing portion apertures for engaging the other casing portion to thereby lock said casing portions together, a handle formed on said latch bar and extending exteriorly of said first casing portion to provide for manual manipulation of said latch bar to effect the locking or unlocking of said casing portions, and a spring plate fixed within said one casing portion adjacent said latch bar, said spring plate

having a projecting portion extending into the path of movement of said handle intermediate the terminal positions of said handle, whereby said spring plate projecting portion 5 tends to hold said handle and hence said latch bar in either locked or unlocked position.

4. A fastener for containers comprising, a pair of complementary hollow casing portions, a swivel latch bar pivotally mounted 10 within one of said casing portions, said latch bar having an operating handle extending exteriorly of said one casing portion to enable manual manipulation of said swivel latch bar, said latch bar having a hook portion arranged 15 to lie within said one casing portion when said operating handle is at one limit of its movement, said hook portion moving outwardly of said one casing portion to engage the other casing portion in locked relation 20 when said operating handle is moved to the other limit of its movement, and a spring plate mounted within said one casing portion, said spring plate having a raised portion projecting into the path of movement of said 25 operating handle intermediate the limiting positions of this handle, whereby movement of this handle from one limiting position to the other is resisted by said spring plate raised portion.
- 30 In testimony, that I claim the invention set forth above I have hereunto set my hand this 5th day of May, 1931.

ALBERT MOMM.
